UNITED STATES PATENT OFFICE

CLARK T. MORSE, OF DETROIT, MICHIGAN, ASSIGNOR, BY MESNE ASSIGNMENTS, TO AMERICAN BLOWER CORPORATION, OF DETROIT, MICHIGAN, A CORPORATION OF DELAWARE

BLOWER

Application filed September 22, 1927. Serial No. 221,375.

My invention relates to blowers.

It is the object of my invention to provide a rigid, quickly assembled, noiseless blower construction, which will eliminate all castings customarily employed in blower constructions, and which will eliminate all noise due to the vibration of the fans and motors.

It is a further object of my invention to provide a common means for supporting the blower housing and the motor and fan in such a way that the motor and fan, while supported from a common support with the housing, will not touch the housing nor communicate the vibrations thereof thereto.

15 It is a further object to provide means of easily and quickly, detachably, mounting the motor with respect to the fan shaft, and resiliently supporting it in position so that the fan and motor will be properly balanced.

20 Referring to the drawings:

Figure 1 is a side elevation of the blower from the motor side;

Figure 2 is a side elevation from the inlet side;

25 Figure 3 is an end elevation on the outlet side;

Figure 4 is a section on the line 4-4 of Figure 1;

Figure 5 is a detail end elevation of the attaching mechanism of the motor to the supporting frame;

Figure 6 is a side elevation in detail;

Figure 7 is a section illustrating the mounting of a bearing and pulley for supporting and driving the shaft instead of the motor;

Figure 8 is a side elevation of Figure 7;

Figure 9 is a similar view showing the rigid supports instead of the flexible supports.

30 Heretofore, it has been the practice in the construction of blowers to provide a metallic casing, the sides of which are either completely or very largely composed of heavy castings, one of which forms the lip and rim adjacent the fan for the directing of air to or from the fan, while the other of the heavy castings served as a bearing support for the fan shaft and served as a motor support either directly or through attaching brackets.

35 Thus, the motor and the fan were directly as-

sociated with and mounted upon the drum-like structure of the fan casing. This resulted in very considerable weight. The castings were expensive and, in large size blowers, difficult to handle because of their 55 weight. This necessitated heavy freight charges and, in operation, the vibration of the motor and fan was directly conveyed to the blower casing and housing. In assembly, much time and labor was lost due to the 60 complicated assembly operations between the sheet metal and casting portions of the blower as well as between the fan and motor installations.

With this understanding of the prior development in the construction of blowers, the 65 novel and advantageous features of my invention will be understood.

I select a scroll casing of sheet metal designated 1 having turned over edges 2 which 70 are U-shaped in cross section.

I then take a side plate, such as 3, and by two operations form a flange 4 and an opening 5. Adjacent this flange 4 I bolt with the bolts 6 an inverted U-shaped horseshoe 75 support of angle iron designated 7, the feet of which 8 rest upon the ground or any other support.

The other side wall 9 has an inwardly 80 formed flange 10, but as I do not cut out this side wall, the bottom 11 of the cup-shaped depression thus formed remains in position. A similar U-shaped angle iron support is mounted adjacent this cup-shaped depression of the side wall 9 and is designated 12. A 85 cross member 13 serves to further brace this inverted horseshoe reinforcement.

One opening for the blower is at 14 and the other opening is through the flange 4 and the passageway formed thereby.

The fan itself is designated 15 and is mounted upon the fan shaft 16, which is also the armature shaft of the motor 17. This motor is suspended by flexible plates 18 preferably formed of rubber and fabric. These plates are wedge-shaped. They are bolted by the bolts 19 to the motor on the motor bracket 20 and by the bolts 21 to the frame bracket 22. The bottom 11 of the side wall 9 is cut away at 23 sufficiently for the passage of the 100

armature shaft so there can be no contact between the armature shaft and the side wall of the casing.

The fan itself can be inserted through the opening 14 of the scroll and moved into position whereupon the motor is inserted with its armature shaft and the fan is attached to the shaft.

It will be noted that the whole structure is supported on the two horseshoe reinforcement members but that support of the motor and fan is independent of the support for the casing. The flexible resilient members 18 provide for the alignment of the motor, its proper balancing and the absorption of all vibration. Any motor of any size may be mounted, the width of the fans may be varied utilizing the same supports and side walls, merely varying the width of the scroll.

20 The advantage of interchangeability of this structure is evident from an examination of Figures 7, 8 and 9.

The shaft 16 may be supported in a bearing 24 in the resilient supports 18 or in the 25 rigid supports 25. This bearing can be mounted in the recess of the cup formed in the side wall while the pulley 26 is mounted beyond the bearing. Thus, the bearing is centrally located between the fan and the pulley 30 and a satisfactory balance can be maintained.

It will be understood that amongst the variations of this arrangement in a construction permitting of a double inlet fan and the permission of the use of a double inlet casing in 35 connection with the fan, such fan being resiliently supported on either one or both sides and the motor being supported resiliently, if desired. Bearings can also be resiliently supported at one or both ends of 40 the fan shaft either with or without motors or pulleys.

It will be understood that I desire to comprehend within my invention such modifications as may be necessary to adapt it to varying conditions and uses.

Having thus fully described my invention, what I claim as new and desire to secure by Letters Patent, is:—

1. In a blower, a sheet metal scroll, sheet metal side walls, a fan within the side walls and scroll, inverted, U-shaped, angle iron, reinforcing members mounted on said side walls, a motor flexibly suspended from one of said U-shaped supports having its armature shaft projecting within said scroll through one of said side walls and the fan mounted thereon in such a manner that the fan and armature shaft as well as the motor do not touch the side walls or the scroll.

60 2. In a blower, a scroll having one end formed in an opening and the edges of the scroll turned over to form U-shaped grooves, sheet metal plates having their edges mounted in said grooves to form side walls of the 65 blower casing of which the scroll is a part, one

of said side walls having an inwardly turned flange adjacent an opening communicating with the interior of the scroll and the other of said side walls being formed into a depressed cup-shaped portion with an opening 70 for receiving an armature shaft, a fan, an armature shaft mounted thereon, a motor adapted to drive said armature shaft, U-shaped angle iron braces and supports mounted on said side walls, and means for flexibly 75 and resiliently mounting said motor on one of said supports.

3. In a blower, a scroll having one end formed in an opening and the edges of the scroll turned over to form U-shaped grooves, 80 sheet metal plates having their edges mounted in said grooves to form side walls of the blower casing of which the scroll is a part, one of said side walls having an inwardly turned flange adjacent an opening communicating with the interior of the scroll and the other of said side walls being formed into a depressed cup-shaped portion with an opening 85 for receiving an armature shaft, a fan, an armature shaft mounted thereon, a motor 90 adapted to drive said armature shaft, U-shaped angle iron braces and supports mounted on said side walls, and means for flexibly and resiliently mounting said motor on one of said supports, within the depression of one 95 of said side walls.

4. In a blower, a scroll having one end formed in an opening and the edges of the scroll turned over to form U-shaped grooves, 100 sheet metal plates having their edges mounted in said grooves to form side walls of the blower casing of which the scroll is a part, one of said walls having an inwardly turned flange adjacent an opening communicating with the interior of the scroll and the other 105 of said side walls being formed into a depressed cup-shaped portion with an opening for receiving an armature shaft, a fan, an armature shaft mounted thereon, a motor adapted to drive said armature shaft, U-shaped angle iron braces and supports mounted on said side walls, and means for flexibly 110 and resiliently mounting said motor on one of said supports, within the depression of one 115 of said side walls, said attachment of the motor to the support being arranged for ready detachability.

In testimony whereof I affix my signature.

CLARK T. MORSE.
